CLAIM

The ornamental design for a puzzle board, as shown and described.

DESCRIPTION

FIG. 1 is a front perspective view of a puzzle board of our new design, showing drawers in an open state;

FIG. 2 is rear perspective view thereof, showing the drawers in an open state;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another front perspective view thereof, showing the drawers in a closed state.

The broken lines in the drawings depict portions of the puzzle board, which form no part of the claimed design.
